UNITED STATES PATENT OFFICE.

JOHN WORLING BEREMAN, OF LYONS, KANSAS.

FOLDING TABLE.

984,529.

Specification of Letters Patent. Patented Feb. 21, 1911.

Application filed May 31, 1910. Serial No. 564,325.

To all whom it may concern:

Be it known that I, JOHN WORLING BEREMAN, a citizen of the United States, and a resident of Lyons, in the county of Rice and State of Kansas, have invented certain new and useful Improvements in Folding Tables, of which the following is a full and clear specification, reference being had to the accompanying drawings, in which—

10 Figure 1 is a side elevation showing the table erected or unfolded; Fig. 2 is a similar view showing the table in the act of folding; Fig. 3 a vertical fragmentary sectional view of one-half the table erected, the parts 15 being shown somewhat enlarged as compared with Fig. 1; Fig. 4 a similar view showing the parts folded; Fig. 5 a bottom view of the table erected; Fig. 6 a perspective view of the table closed; Fig. 7 a bottom 20 view of one corner of the table showing the parts folded.

The object of this invention is to so construct the table that it may be readily folded and unfolded and when folded shall occupy 25 a minimum of space so that it may be conveniently stored and carried about from place to place, this compactness and portability adapting the table especially for use in connection with surgical operations and 30 massage, osteopathic and other treatments, the parts being so constructed and arranged that when the table is erected it will have a firmness and rigidity equal to a non-folding table, as more fully hereinafter set forth.

35 The table top is divided transversely midway its length to form two sections *a* each of which is provided at its side edges and its outer-end edge with a depending flange *b*; and each of which is also provided near its 40 outer end with a pair of legs *c* pivotally connected at their upper ends to the table top by horizontal pivots *c'*, these pivots being supported in suitable metal strips *d* rigidly fastened to the under side of the table top.

45 There are four of these metal strips *d* two being attached to each of the table top sections and the pair carried by each section have their inner ends in abutting relation to the corresponding strips on the opposite 50 section. The abutting ends of each pair of strips *d* are hinged together by a plate *e*. The strips *d* are fastened to the table top sections in a vertically edge-wise position, and the hinge plates *e* are like-wise edge- 55 wisely vertical, so that the strips *d* contribute rigidity to the table top while the plates *e*

adapt the two sections of the table to be folded one upon the other with their edge flanges *b* in abutting relation, so that when thus folded they form a box-like casing 60 which will inclose the folded legs and the operating parts.

Each of the hinge plates *e* depends below the lower edges of the strips *d* and pivotally attached to each of its corners is a truss rod *f* 65 which extends outwardly toward the end of the table and has pivotally connected to its outer ends a short link *f'*. The end of this link *f'* overlaps and is pivotally connected to the upper end of a leg brace *g* which is 70 pivotally connected to the adjacent one of the strips *d* in such manner that the leg brace lies in the same vertical plane with the truss rod *f*. The leg brace *g* at its lower end lies 75 against one side of the adjacent table leg and is slidingly connected thereto by an eye or staple *h* carried by the leg, the brace being prevented from withdrawal from the staple or eye by means of a lug *j* projecting upwardly and outwardly from its lower ex- 80 tremity.

I have described the table as it appears when fully open. In this position the truss rods *f* and their link extensions *f'* are in alinement and are held in that position by 85 the legs and their braces *g*. In folding the table, it is obvious that the act of bringing one of the table top sections over upon the other table top section will cause the truss rods and their link extensions to swing the 90 upper ends of the brace rods toward the ends of the table and thus cause the brace rods to swing the legs simultaneously inwardly, as shown especially in Fig. 2. These movements of the parts continue until the 95 legs are nearly folded and the table top sections are brought quite close together, whereupon the upper ends of the braces *g* strike against the under edges of the truss rods where they are connected to their link extensions and break upwardly the toggle formed by the truss rods and their links, thus permitting the parts to continue in their 100 folding action. When completely folded, as shown in Fig. 4, the legs will lie within 105 their respective table top sections, the truss rods will lie in a horizontal position adjacent to the respective table top boards and the leg braces will lie directly under and edgewise in alinement with the truss rods. 110 In unfolding or erecting the table, it will be observed that the mere act of unfolding the

- top sections will simultaneously unfold the legs and bring the leg braces and the toggle trusses into the position shown in Fig. 3, in which position the leg braces and the toggle trusses will be in locked relation, which relation cannot be disturbed when the table is in its usual position except by breaking upwardly the joint between the table top sections and simultaneously swinging in 10 both the leg structures. It will therefore be observed that when the table is erected it will have the maximum of rigidity and at the same time will be practically locked against accidental collapsing.
- 15 Having thus fully described my invention, what I claim as new and desire to secure by Letters Patent, is—
1. In a folding table, the combination of a table top transversely divided centrally, 20 hinge plates pivotally connected to the same and depending below their points of connection to the sections, a pivoted leg structure for each table top section, a pair of leg braces slidably connected to each leg struc-

ture and pivotally connected to the adjacent 25 table top section, and a toggle truss connection between each leg brace above its pivot and the depending corner of the adjacent one of said hinge plates, for the purpose set forth.

2. In a folding table, the combination of a table top transversely divided, hinge plates pivotally connecting the table top sections and depending below their points of connection therewith, a pivoted leg structure attached to each table top section, leg braces connecting each leg structure to its table top section, and a pair of rods connecting the depending portion of each hinge plate to the adjacent leg brace, for the purposes 35 set forth.

In testimony whereof I hereunto affix my signature in the presence of two witnesses this 21 day of May 1910.

J. WORLING BEREMAN.
